Application filed January 29, 1912. Serial No. 674,021.

REISSUED

To all whom it may concern:

Be it known that I, EDWARD W. BRACKENBURY, a subject of the King of England, residing at Milwaukee, in the county of Milwaukee and State of Wisconsin, have invented a new and useful Tilting Device for Concrete-Mixers, of which the following is a specification.

My invention relates to improvement in means for tilting the drum of a concrete mixer to discharge the same and to return the drum to its initial position; and the objects of my invention are to make a simple, durable and efficient machine for this purpose which shall fully satisfy all the limitations imposed on a machine of this character. I attain these objects by the mechanism illustrated in the accompanying drawing which forms a part of this specification, and in which—

Figure 1 shows an end elevation of the machine applied to a concrete mixer. Fig. 2 shows a side elevation of the machine, the parts involved in the tilting mechanism being shown in section taken on a vertical central plane.

The same reference characters refer to the same parts in the different figures.

(1) is the drum of the concrete mixer attached to the gear ring (2) by which it is rotated, supported on rollers (3), only one being shown, and guided by edge rollers (4) in the structural frame (5). This frame (5) is carried by, and tiltable around trunnions (6), only one being shown, and the drum is rotated by means of the shaft (7) concentric with the trunnion, miter gears (8) and (9) and the spur pinion (10) engaging the gear ring (2). The trunnions are supported by pedestals (11), one being shown, and power is applied through the gear (12).

The mechanism described thus far constitutes a rotating concrete mixer which is tilted to discharge, which forms no part of my present invention, and is illustrated merely to show the application of my device. Further detailed description of the mixer is therefore unnecessary.

On the driving shaft (7) of the machine which is to be tilted is placed a gear (13) which drives and operates the tilting mechanism through the spur gear (14) and its attached miter gear (15) rotating on the pin

(16) which is secured in the bracket (17) which forms a part of, or is attached to the pedestal (11). Also supported in bearings on the bracket (17) is the clutch shaft (18) on which the miter gears (19) and (20) revolve loosely in opposite directions, but are restrained from longitudinal movement along the shaft. Each of these gears has its hub formed to constitute a tapering friction member over which the hollow or cup-like friction members (21) and (22) are adapted to engage. These cup members are splined on the clutch shaft to revolve therewith and are movable along the shaft by split collars (23) and (24) engaging grooves in the hubs of the cup members, and also pivoted in the levers (25) and (26). It is obvious that as the gears (19) and (20) with their friction members revolve in opposite directions, the shaft (18) will revolve in one direction or the other according to which cup friction member is engaged, or will not revolve at all when both cup friction members are disengaged. The gears (25) and (26) on the clutch shaft and screw shaft (27) respectively communicate the movement of the former to the latter. This screw shaft is housed in bearings on the pedestal (11), and has in engagement with its threads a nut (28) which is guided by and slides freely on a rod (29). A lug projects from this nut and carries an anti-friction roller (30) engaging in a slot or groove (31) in the bracket (32) which is secured to the swinging trunnioned frame (5). Thus as the nut (28) travels one way or the other along the screw, it swings the frame (5) and drum (1) in a corresponding direction. In order to limit the motion of the nut and consequently the tilting of the drum, the nut carries a projecting finger (33) which engages alternately with two tappets (34) and (35) which are disposed on a link (36) connecting the lower ends of the levers (25) and (26), which levers are pivoted on the bracket (17) at fulcrums (37). The tappets (34) and (35) are so disposed that they will be engaged by the finger (33) when the drum is in its limiting positions, and further movement of the nut disengages the clutch and the drum remains either tilted or level, in the position in which it was left by the tilting mechanism until the operator, by means of the attached levers

(25) and (26), engages the clutch which was disengaged during the previous operation.

There are several limitations to which this device is subjected all of which are perfectly provided for. The frame must be locked when the clutches are disengaged to maintain the drum in exact position for loading and discharging, and this feature is provided for by the screw and nut engagement.

- 10 The large speed reduction from the driving shaft is also conveniently provided for by the screw. The disengaging tappets are operated by a part that has a long range of motion, and the entire tilting device is self contained with the machine which it operates. If in emergency it becomes necessary to tilt the machine by hand, this can be done by removing the gear (25) and attaching spokelike handles to the gear (26), or anywhere on the screw shaft (27).

Having now fully described a practical form, which the invention may take, what I claim as my invention is—

1. In combination with a machine to be tilted, a tilting device comprising a screw and nut, the latter engaging the part to be tilted and means for rotating the screw in either direction.
2. In combination with a device to be tilted, tilting means comprising a screw, means for rotating the screw in either direction, and intermediate means engaging the

screw and movably engaging the part to be tilted at a point remote from the tilting axis.

3. In combination with a device to be tilted, a tilting device comprising a screw, means for rotating the screw in either direction, and intermediate means engaging the screw and movably engaging parallel shoulders on the part to be tilted.

4. In combination with a device to be tilted, a tilting device comprising a screw and nut, means for rotating the screw in either direction, and shoulders on the tilting part engaging said nut.

5. In combination with a machine to be tilted, a tilting device comprising a screw and nut, means for rotating said screw in either direction, means on the part to be tilted adapted to engage said nut, and means for disengaging said screw from its actuating means.

6. In combination with a machine to be tilted, a tilting device comprising a screw and nut, means for rotating said screw in either direction, means on the part to be tilted adapted to engage said nut, and means actuated by said nut for disengaging said screw from its actuating means.

EDWARD W. BRACKENBURY.
